(57) **CLAIM**

The ornamental design for a swaddling garment for an infant as shown and described.

DESCRIPTION

FIG. 1 is a front elevation view of a swaddling garment of the present invention, with an elongated opening disposed in a chest region of an anterior covering and an elongated opening disposed adjacent a pelvic crotch region of the anterior covering;

FIG. 2 is a rear elevation view of the swaddling garment of FIG. 1, with an elongated opening disposed in a back region of a posterior covering and an elongated opening disposed adjacent a pelvic crotch region of the posterior covering;

FIG. 3 is a right elevation view of the swaddling garment of FIG. 1;

FIG. 4 is a left elevation view of the swaddling garment of FIG. 1;

FIG. 5 is a top plan view of the swaddling garment of FIG. 1; and,

FIG. 6 is a bottom plan view of the swaddling garment of FIG. 1.

The dot-dashed broken lines depict portions of the swaddling garment that form no part of the claimed design.

1 Claim, 4 Drawing Sheets
